PIANO ACTION

Phillip J. Roehrig, De Kalb, Ill., assignor to The Wurlitzer Company, Chicago, Ill., a corporation of Ohio
Filed Apr. 18, 1960, Ser. No. 22,919

12 Claims. (Cl. 84—240)

This invention relates to new and useful improvements in piano actions, and more particularly to such improvements in actions of the drop or inverted sticker type used in instruments having strings lying in a vertical plane, such as upright or so-called spinnet pianos.

The grand piano has usually been preferred over upright or so-called spinnet pianos in that the "touch" and rapid repetition are generally preferred by artists. In the grand piano, the strings lie in a horizontal plane and the hammer travels substantially vertically so that gravity acts to return the hammer from its advanced striking position. In hammer actions for strings lying in a vertical plane, the force of gravity usually has little effect except just prior to striking position and prior to reaching a position of rest. For this reason, upright pianos are often somewhat inadequate in permitting rapid, repetitive striking of a key prior to complete release of finger pressure thereon. In other words, in such instruments, often the hammer and jack are not properly positioned for rapid repetition of the key action. There have been efforts to correct this inadequacy in upright type pianos but often the corrective steps have resulted in sacrificing the desired "touch" of the action.

With the above in mind, one of the principal objects of the present invention is to improve the permissive repetitive key action in an upright type piano without sacrificing the desired "touch" of the action.

Another object of the invention is to provide an action of the above type wherein the conventional bridle tape and wire as well as the conventional jack spring are eliminated but with maintenance of the desired "touch" and permissive rapid repetition of the key action.

A further object of the invention is to provide an action of the above type wherein the jack finds its desired position in engagement with the hammer knuckle prior to the hammer reaching a position of rest so that depression of a key may be rapidly repeated without the necessity of the key returning to its fully released position.

A still further object of the invention is to provide an action of the above type wherein the hammer and jack springs are relatively coordinated and positioned to effect the aforesaid desired action.

A still further object of the invention is to provide an action substantially of the above type wherein the cooperative abutting engagement between the jack and hammer knuckle is such as to substantially minimize the transmission of noise during operation of the action.

The invention still further aims to provide an action substantially of the above type which is relatively compact in its composite assembly but wherein the several parts are readily accessible for adjustment, replacement and the like.

The above and other objects of the invention will in part be obvious and will be hereinafter more fully pointed out.

In the accompanying drawing:

FIG. 1 is an end view of the action at rest but with the various fixed rails shown in section;

FIG. 2 is an enlarged perspective view of the auxiliary whip;

FIG. 3 is a fragmentary end view showing a modified form of interconnection between the auxiliary whip and a key.

Referring to the accompanying drawing, the key bed 10 carries a balance rail 11 having screw-type adjustable

2

balance key pins 12. There is a forward rail 14 on the key bed carrying a front key pin 15. A key 16 is mounted in known fashion with respect to the balance or leveling pins 12 and the front key pin 15. The rear or inner end of the key 16 has projecting therefrom a spoon 17 which serves to actuate the sticker as will presently appear. Alternatively, reference being had to FIG. 3, the inner end of the key may be recessed to provide a projecting portion 18 serving to actuate the sticker as will be described below. There is a felt 19 on which the inner end of the key is positioned when at rest.

The sticker 20 is of the drop or inverted type and is threadedly connected at its upper end to a screw 21 having a screw head 22 and washer 23 engaging an auxiliary whip 24. As illustrated in FIG. 2, the auxiliary whip 24 includes a rearward apertured lug 25, which is pivotally connected to an auxiliary whip flange 26 secured to a fixed auxiliary rail 27. The opposite end of the auxiliary whip 24 is provided with a longitudinal slot 28 opening at the forward end thereof and through which the screw 21 may be assembled with the auxiliary whip. The washer 23 is seated within a recess 29 in the top surface of the auxiliary whip. The under surface of the forward end of the auxiliary whip carries a felt 30 with which the spoon 17 is in engagement for initiating operation of the action. It is to be noted that the screw head 22 is readily accessible from above for adjustment of the sticker 20 with respect to the auxiliary whip 24 and thus eliminates the necessity for a capstan screw usually carried on the adjacent end of a key. A felt 31 is disposed between the auxiliary rail 27 and the inner end portion of the auxiliary whip 24 to limit downward travel of the auxiliary whip and to hold the parts in normal position even when the keyboard is removed.

The lower end of the sticker 20 is pivoted, as at 32, to the forward free end of the main whip 33 which, in turn, is pivoted, as at 34, to a whip flange 35 carried by the main rail 36. Inwardly of the whip pivot 34, the whip carries a spoon 37 to actuate the damper head 38 against the action of a damper spring 39 in known manner.

Intermediate the pivots 32, 34, the whip 33 carries an upwardly extending jack flange 42 to which a jack 43 is pivoted, as at 44. The jack is provided with a forwardly extending abutment 45 carrying a felt 46 engageable with a regulating rail button 47 during the action to pivot the jack away from the hammer knuckle as will be described below. The button 47 is threadedly carried by a regulating rail 48 and is adjustable from above by means of a tool engaging formation 49. The regulating rail 48 has secured thereto a hairpin type jack spring 51 having a curved free end portion riding in a longitudinal recess 52 in the jack 43. The whip 33 also carries a backcheck wire 53 which has secured to the upper end thereof a backcheck 54.

The main rail 36 carries a knuckle flange 55 to which is pivoted a hammer knuckle 56. The knuckle 56 is provided with a downwardly convex recess 57 in which is secured a felt 60 over which a buckskin 61 is positioned. In order to reduce noise instant to actuation of the knuckle

60 by the jack, the felt 60 is secured in the recess 57 by one or more spots of glue 58. Preferably, the glue spots 58 are spaced so that the felt 60 is unsecured in the region encountering the effort of the jack in actuating the knuckle 56. Without any glue barrier in this region, it has been found that the noise of the action is materially reduced. The knuckle 56 carries a forwardly projecting catcher stem 63 to the end of which is secured a catcher 64 for cooperation with the backcheck 54.

The knuckle 56 carries a hammer arm 66 with a hammer head 67 at the free end thereof. The hammer arm 66 engages a fleted hammer rail 68 in the position of rest.

The spring rail 71 carries a knuckle spring 72 with the lower free end thereof engaging the knuckle to urge the same toward the position of rest. A string S is illustrated as being mounted in more or less conventional manner.

In operation, the key 16 is struck to elevate the inner end thereof and this elevates the auxiliary whip 24 and the main whip 33 through the connection provided by the sticker 20. With such upward pivotal movement of the whip 33, the jack 43 is moved upwardly and by reason of its engagement with the knuckle 56, the hammer is impelled toward the string but just prior to engagement between the hammer and string, the felted abutment 45 engages the button 47 to pivot the jack 43 away from the knuckle 56 and against the pressure of the jack spring 51. During this upward movement of the whip 33, the backcheck 54 is moved in unison therewith and the spoon 37 urges the damper 38 away from the string and against the action of the damper spring 39. After striking, the hammer 67 rebounds under influence of the hammer spring 72 to a position for checking between the backcheck 54 and the catcher 64 until the key is released. At this time, the whip 33 begins to fall toward the position of rest and the jack spring 51 pivots the jack 43 into wedging engagement with the felted knuckle 56. The spring 51 is weaker than would be a jack spring positioned between the abutment 45 and whip 33 but the desired mechanical advantage is obtained with the end of the spring 51 engaging the jack 43 near the free upper end of the jack so that the jack and knuckle may be positioned for repetitive action when the key has returned only about half way to the normal position of rest. The "touch" is thus maintained to approximate that of a grand piano action in that a heavy or stiff jack spring is not required. With the lighter jack spring, return of the jack may be slowed up slightly but with the accurately curved buckskin 61, the jack will find its position relative to the knuckle by being wedged along the buckskin surface in time to permit rapid repetitive key action. With this structure, it is possible for the hammer to rebound a slightly greater distance before checking and the position of checking may be more stable upon compression of the felt on the backcheck.

As will be appreciated, the principal adjustments may be made from above. Thus, the screw 21 can be adjusted from above with respect to the sticker and this can be accomplished with the keyboard removed since the felt 31 will maintain the auxiliary whip 24 in proper position. Likewise, the adjustment of the button 47 can be accomplished from above by a tool engaging the tool formation 49. In this connection, it is to be noted that the button 47 has a rounded surface engageable with the felt 46. Thus, the depression formed in the felt 46 during use remains in a constant position relative to the adjustment of the button so that the adjustment is only a function of the screw-thread. In instances where the adjustable button is itself felted, the packing of the felt is off-center so that when the felted button is rotated for adjustment, the off-center packed portion is turned and the adjustment necessarily is a function of the off-center position of the packed felt and the screw thread. With the present arrangement, extremely fine and accurate adjustment results.

The elements 12' surrounding the balance key pins 12 and between the key 16 and balance rail 11 comprise flanges fixed on the key pins 12. Thus, key levelling is effected from above the keyboard by threading the screws 12 in or out, whereby to raise or lower the flanges 12'. As will be understood, the key pins 12 and the balance rail 11 are disposed within the piano case (not shown).

Thus, it will be seen that the adjustments of the piano actions, comprising the balance key pins 12, the sticker 20 and screw 21, and the regulating rail button 47 all are adjustable from above, whereby it is unnecessary to reach the action from an inconvenient underside location.

While one form of the invention has been shown for purposes of illustration, it is to be clearly understood that various changes in the details of construction and ar-

rangement of parts may be made without departing from the spirit and scope of the invention as set forth in the appended claims.

I claim:

1. An action for a piano with strings disposed substantially vertically; and comprising a key having inner and outer ends, a depending sticker disposed inwardly of the inner end of the key, an auxiliary whip, fixed frame means, means pivotally mounting said auxiliary whip on said fixed frame means at a position spaced inwardly from the inner end of the key with said auxiliary whip extending toward said inner end of said key, said auxiliary whip supporting the upper end of said sticker with the outer end of said auxiliary whip disposed closely adjacent the inner end of said key, mutually interengaging means on the auxiliary whip and key for actuating the sticker in response to key depression, a main whip pivotally mounted on a fixed frame member and pivotally connected to the lower end of said sticker, a pivoted hammer and arm assembly including a knuckle, a jack pivotally connected to said whip and engageable with said knuckle for impelling the hammer toward striking position, jack spring means mounted on said fixed frame means and bearing on said jack above its pivotal connection with said main whip for positioning the jack for engagement with the knuckle during return of the action toward a position of rest, a depending stop button carried by said fixed frame means and engageable with an abutment portion on said jack for disengaging the free end of the jack from said knuckle and against the action of said jack spring means during movement of the action towards striking position, a catcher associated with the hammer and arm assembly, a backcheck carried by said whip for cooperation with said catcher, and hammer spring means urging the pivoted hammer and arm assembly toward a position of rest.

2. An action for a piano as claimed in claim 1, wherein the depending sticker is fixed against rotation about its own axis and includes a screw element projecting through the auxiliary whip and engageable thereabove for adjustment.

3. An action for a piano as claimed in claim 2, wherein the auxiliary whip is provided with a longitudinal and vertical recess opening at the outer end thereof facilitating assembly and disassembly of the sticker and screw element.

4. An action for a piano as claimed in claim 1, wherein the auxiliary whip is substantially level with the key for ready access thereto.

5. An action for a piano as claimed in claim 1, wherein the interengaging means comprise a felt on the bottom surface of the outer end of the auxiliary whip, and a spoon on said key engageable with the said felt.

6. An action for a piano as claimed in claim 1, wherein the interengaging means comprise a felt on the bottom surface of the outer end of the auxiliary whip, and recess means in the inner end of the key providing an offset shoulder engageable with the said felt.

7. An action for a piano as claimed in claim 1, wherein there is provided a felt between the inner end of the auxiliary whip and the supporting fixed frame member for maintaining the action in position upon removal of the keyboard.

8. An action for a piano as set forth in claim 1 wherein said knuckle has a downwardly opening recess therein, and a felt disposed in said recess for engagement by said jack, said felt being secured to the knuckle at limited and spaced points to reduce noise.

9. An action for a piano as claimed in claim 8, wherein the points at which the felt is secured to the knuckle are removed from the area of contact between the felt and the jack.

10. An action for a piano as set forth in claim 1 wherein said depending stop button is provided with a smooth, rounded under surface, and wherein the engageable abut-

ment portion on said jack has a felt thereon for engagement with said stop button smooth, rounded under surface.

11. An action for a piano with strings disposed substantially vertically; and comprising a key, having inner and outer ends, a depending sticker with means adjacent the upper end thereof for operative engagement with the key, fixed frame means, a whip having inner and outer ends and pivotally mounted on said fixed frame means with its outer end pivotally connected to the lower end of said sticker, a pivoted hammer and arm assembly including a knuckle, a jack pivotally connected to said whip intermediate the ends thereof and including an abutment, jack spring means mounted on said fixed means and bearing on said jack above its pivotal connection with the whip for positioning the jack for engagement with the knuckle during return of the action toward rest position, a stop button carried by said fixed frame means and cooperable with said abutment for disengaging the free end of said jack from said knuckle and against the action of said jack spring means during movement of the action toward striking position, a catcher associated with the hammer and arm assembly, a backcheck carried by said whip for cooperation with said catcher in checking

movement of the hammer and arm assembly, and hammer spring means urging the pivoted hammer and arm assembly toward a position of rest and coordinated with said jack spring means to constitute substantially the sole mechanical force for restoring the hammer and arm assembly toward rest position, the hammer spring means and the jack spring means being relatively coordinated in spring force to permit the jack to assume its operative engagement with said knuckle when the key is returned only about half way to its rest position thereby permitting rapid repetitive action of the key without complete release of finger pressure from the key.

12. An action for a piano as claimed in claim 11, wherein the jack spring means comprises an elongated spring element riding in a groove along the adjacent jack surface.
